UNITED STATES PATENT OFFICE

2,481,785

BOAT STRUCTURE

Rolland C. Sabins, Seattle, Wash.

Application July 25, 1945, Serial No. 607,024

7 Claims. (Cl. 114—82)

1

My invention relates to boat construction and especially to the bulwarks and deck margin structure incorporated in it. Such structure is particularly valuable for boats having metal bow and stern tank sections joined by a wooden midship section, as disclosed in my companion application Serial No. 543,106, filed July 1, 1944, matured into Patent 2,473,039 on June 14, 1949, but it may be employed to advantage in an otherwise conventional type of boat.

Heretofore it has been the practice customarily to extend the frames of a boat hull upwardly substantially to the top of the bulwarks and to notch the decking to fit around them. Shrinkage of the decking and weaving of the boat structure under the stresses of heavy weather prevented the crevices between the decking and the frames from remaining water-tight even though calked thoroughly during construction of the boat. Seepage of water through such crevices induced rotting of the frames immediately below the deck.

The staves forming the bulwarks in a boat of conventional construction do not afford very great longitudinal stiffness, and particularly in a boat incorporating metal bow and stern tanks, as disclosed in my aforesaid patent application, it is important that the midship portion of the boat joined to the stern and bow tank sections include structure capable of withstanding large bending loads, to relieve the joints between the metal and wooden section from stress as far as possible.

It is therefore a principal object of my invention to provide a bulwark structure capable of effectively resisting great bending loads, which is structurally continuous substantially from the bow to the stern of the boat, and preferably is continuous entirely around the boat.

It is a further object to terminate the frames immediately below the decking of the boat and to extend such decking outward over the upper ends of the frames, while at the same time providing a bulwark structure which can be secured satisfactorily to the skeleton of the boat below the decking, and which will afford a construction even stronger than the conventional frame and planking bulwarks. In achieving such object a special type of bulwark construction is utilized, and this is integrated with the hull structure in a unique fashion.

Additional objects and advantages of my invention will be discussed in the following description of construction which I now prefer, but it will be appreciated that changes within the spirit of my invention may be made in the construction described hereafter.

2

Figure 1 is a side elevation view of a boat incorporating my deck margin and bulwark construction.

Figure 2 is a longitudinal sectional view through the midship portion of the boat showing my bulwark structure in elevation.

Figures 3, 4, 5, and 6 are fragmentary athwartships sections taken on lines 3—3, 4—4, 5—5, and 6—6, respectively, of Figure 2.

10 Figure 7 is a side elevational view with parts broken away, and

Figure 8 is a plan view of a scupper spacing block.

The boat includes a midship portion 1 which 15 may be of conventional wooden construction below the deck. Such wooden portion may be joined to a metal bow tank 10 and to a metal stern tank 11 in accordance with the disclosure of my application Serial No. 543,106, mentioned above, but for the purpose of the instant invention it is not necessary that the hull be of such composite wood and metal construction. The nature and arrangement of the cabin and other superstructure, with the exception of the bulwarks, is immaterial to the 20 present invention, that illustrated in Figure 1 merely being representative.

The hull of the boat is composed of frames 2, to the outer faces of which the planking 20 is secured as usual. The clamp 21 extends from bow 25 to stern across the inner faces of the frames and is secured to them in suitable fashion, while the outer edge of the shelf 22 abuts the inner face of the clamp. The shelf is bolted to the clamp so that the upper shelf face is coplanar with the upper edge of the clamp. The outer ends of the deck beams 23 then rest on the shelf and the clamp.

In the forward portion of the boat the fore shelf 22' is located considerably above the aft shelf and 30 consequently does not engage the clamp 21, but is notched appropriately to fit around the frames, and is bolted to them. The deck beams 23' adjacent to the rearward end of shelf 22' rest on such shelf, but the deck beams 23'' farther forward are 35 spaced a substantial distance above the shelf 22' and are supported from the bulwarks, as will be described.

It will be noted particularly from Figures 2 and 5 that the frames 2 extend upward only to the 40 decking of the main deck 24, which is preferably composed of a double thickness of waterproof plywood, each plywood layer preferably being at least $\frac{3}{4}$ of an inch thick. In the region of the scupper 25 the decking not only extends outward 45 over the upper ends of frames 2, but also over

the upper edge of the planking 20, so that its outer edge lies flush with the outer face of such planking, as shown in Figure 6. Forward and rearward of the scupper the decking 24 terminates at the inner face of the planking and the latter extends upward beyond the deck level, in the manner shown in Figure 5.

The main bulwarks 3 are of laminated construction, the joints between the laminae preferably extending generally vertically and substantially perpendicular to the decking 24. This structure will be prefabricated in sections extending along the margin of the boat deck. Thus the stern portion of the bulwarks may be made as a single horseshoe section, or, if such a structure would be too large to handle easily, in a plurality of curved sections which could be arranged in end to end relationship to form the stern bulwarks. Similarly the bulwarks along the sides can be made in sections of suitable length and assembled end to end. When installed in the boat, all adjacent sections are secured together by scarf joints so that the entire main bulwarks along both sides of the boat and around the stern will constitute an integral structure.

As shown in Figures 1 and 2 the fore bulwarks 30 project considerably above the main bulwarks 3, and the aft portions of such forward bulwarks overlie the forward portions of the main bulwarks. Like the main bulwarks the forward bulwarks are of laminated construction, in which joints between the laminae extend generally vertically and substantially perpendicular to the deck. The foredeck 26 is disposed at the upper edge of the forward bulwarks structure 30, but such structure is nevertheless designated bulwarks because of its relationship to the main deck 24. Between the main deck and the foredeck is an intermediate or bridge deck 27, which is of slight extent fore and aft.

The construction by which the main bulwarks are secured to the boat hull is shown in Figures 2, 5, and 6. At stations spaced reasonably closely hooked tie rods 31 having their hooked ends hooked under the clamp 21 extend upwardly between the frames 2, between the clamp and planking 20, and between the deck beams 23, through the decking 24, and through bulwarks 3 intermediate their inner and outer faces. The short ends of such hooks may stop short of the shelf 22, or may actually engage the lower face of such shelf and constitute additional means for supporting it. The upper ends of tie rods 31, which lie immediately below the upper edge of the bulwarks, are threaded to receive nuts for drawing the bulwarks downward towards the hull.

To provide scupper openings scupper blocks 32, preferably of circular shape, are interposed between the lower edge of the bulwarks 3 and the decking 24. As shown in Figures 7 and 8 each block is slightly wedge-shaped to engage contiguously such bulwark's edge and decking, and has an aperture 33 through it for passage of a tie rod 31. As shown in Figure 6 the diameter of each scupper block preferably is equal to the combined thickness of the bulwarks 3 and planking 20. In any event the combined lower surface area of all the blocks should be large enough, and the spacing between adjacent rods 31 should be small enough, so that ample bearing surface of the scupper blocks on the decking 24 is afforded to permit the nuts on the tie bolts to be drawn down tightly.

The upper edge of the bulwarks is recessed appropriately to receive the tie bolt nuts and such

nuts and the upper edge of the bulwarks are covered by a cap 34 preferably of hardwood. Although the tie bolts alone are probably adequate to anchor the bulwarks securely to the hull, the bulwarks may be held against tilting by one or more knees 35 located in the angle between the bulwarks and the decking. Preferably each knee is located directly above a deck beam 23, and may be bolted to the bulwarks and planking covering its outer side, and to the decking, a deck beam, and the shelf 22 below it, as shown in Figure 6. Both of the generally upright anchor bolts pass through such deck beam, and one or both of them may pass through the shelf.

It will be seen from the illustration in Figures 2 and 6 that the decking 24 forms a solid sheathing over the upper end of frames 2 and the upper edge of the planking 20, thus serving as a complete protection for these parts from seepage of water below the deck. The sponson 28 is then applied to the exterior of the planking in a position overlapping the edges of the decking layers so that the upper edge of the sponson forms a smooth continuation of the deck at the outer side of the scuppers 25. The guard 29 is secured to the outer side of the sponson.

Forward of the scuppers spacer blocks 32 are not utilized, as shown in Figure 5, but instead the lower edge of the main bulwarks seats directly on the decking 24. Although such decking extends outward over the upper ends of frames 2 to the outer side of the prefabricated bulwarks, the planking 20 is carried continuously upward past the main deck to the cap 34. At this location, however, the cap does not form the upper member of the bulwarks structure, for the aft portion of the fore bulwarks 30 extends rearwardly to overlie the main bulwarks 3. This portion of the fore bulwarks is secured to the main bulwarks by long lag screws spaced at appropriate intervals and extending downward through the fore bulwarks into the main bulwarks, as indicated in Figure 2. The outer side of the fore bulwarks may be covered by a plywood facing 36 extending from the fore bulwarks' cap 31 down to cover the outer edge of the lower main bulwarks' cap 34.

As shown in Figure 2 the main bulwarks 3 terminates forwardly at the rearward edge of the intermediate deck 27. Forward of this location, as illustrated in Figure 4, the lower edge of the fore bulwarks 30 rests directly upon the deck, which is supported upon the higher deck beams 23 and shelf 22. Here the bulwarks structure is the same as that of the portion of the fore bulwarks, extending rearwardly from this location, except that the bulwarks are higher and the cap piece 31 is formed by a different piece extending forwardly to the stem of the boat.

From the intermediate deck 27 forward the fore bulwarks 30 are of substantially constant height. Since the foredeck 26 and its beams 23 are spaced above the shelf 22, however, it is necessary to provide an intermediate structure between the shelf and the lower edge of the bulwarks. This structure takes the form of the base 38, preferably of laminar construction, which is fabricated integrally with the fore bulwarks. This base, as shown in Figure 3, is thicker than the bulwarks, but its outer side is flush with the outer surface of the upper bulwarks portion. The part of such base projecting inward beyond the bulwarks rests on the shelf 22 and covers the upper ends of frames 2, and long spikes driven upward through the shelf into the bulwarks secure them in place. The lower side of this base

is recessed to receive the planking 20 so that its upper edge does not project beyond the outer side of the base. The entire outer surface of the bulwarks, including its base, is covered by the plywood facing 36.

The upper edge of the fore bulwarks 30 is notched at intervals to receive the ends of the foredeck beams 23" which are spiked to the bulwarks, and thus supported solely from the bulwarks. Such beams serve to tie together the upper edges of the bulwarks on opposite sides of the boat to prevent them from tilting outwardly or inwardly, and these beams are assisted by a bulkhead between the bridge deck 27 and the foredeck 26 also interconnecting the opposite bulwarks. In this respect the foredeck beams and such bulkhead perform a function for the fore bulwarks somewhat similar to that which the knees 35 serve with respect to the main bulwarks.

The decking 26 extends entirely across the upper edge of the fore bulwarks, as shown, to protect the edges of the bulwarks plies from the weather. Forward of intermediate deck 27, therefore, the upper edge of the forward bulwarks will be recessed to receive the decking 26, or a filler piece will be applied to the bulwarks behind the foredeck, so that its upper surface will be flush with the upper edge of the fore bulwarks in the region of the intermediate deck. The cap strip 37' will then lie flat against the upper edge of the bulwarks rearwardly of the foredeck and will form a marginal or bulwarks strip forward of the intermediate deck. Preferably the cap piece 37' projects a substantial distance beyond the outer side of the bulwarks, and a facing strip 39 may be secured over the edge of the decking to protect it, the outer side of such strip preferably being disposed substantially flush with the outer edge of cap strip 37', as shown in Figures 3 and 4.

It will be seen that with a construction of the type described extending entirely around the boat, the bulwarks are very substantial, are securely attached to the hull, and are well braced so that they are not likely to be injured by striking a dock or other object. Although the decking is allowed to extend outward to cover and protect from the weather the frame ends and other structure below it, my bulwark structure is even stronger than the conventional type. Moreover, the bulwark structure, being very rigid and extending continuously from the bow to the stern, constitutes an efficient beam which stiffens the boat over its entire length without occupying appreciable space useful for cargo or other purposes. Especially is this type of construction desirable in a boat such as disclosed in my application Serial No. 543,106 incorporating metal tanks as bow and stern sections. Despite the structural advantages and protection against seepage of water afforded by my invention, the bulwarks can be prefabricated economically by being formed exactly to the desired curvature to conform with the lines of the boat before they are installed. Thereafter it is merely necessary to secure them in place by the hooked tie bars, lag screws and spikes in the manner described above.

I claim as my invention:

1. In a boat hull structure, upright frames, an exterior wall secured to said frames, a clamp element extending lengthwise of the hull and secured to said frames, decking above said clamp and extending outward above the upper ends of said frames to said exterior wall, bulwarks above said decking, and hooked tie rods having lower hooked ends in hooked engagement with said

clamp, extending upward between said frames and through said decking, and secured to said bulwarks to anchor them firmly to the hull.

5 2. In a boat hull structure, decking, hull framework beneath said decking, bulwarks above said decking, scupper spacing blocks interposed between the upper surface of said decking and the lower side of said bulwarks to support the latter from said decking, and tie rods, each passing through said decking and a scupper block, locating said scupper blocks relative to said decking, the lower ends of said tie rods being secured to said hull framework, and the upper ends of said tie rods being secured to said bulwarks to anchor them firmly to the hull.

3. In a boat hull structure, upright frames, planking secured to said frames and forming an exterior hull wall, a clamp element extending lengthwise of the hull and secured to the sides of

20 said frames opposite said planking, decking above said clamping and extending outward above the upper end of said frames and across the upper edge of said planking, bulwarks above said decking, scupper spacing blocks interposed between

25 the upper surface of said decking and the lower side of said bulwarks to support the latter from said decking, and hooked tie rods having lower hooked ends in hooked engagement with said clamp, extending upward between said frames

30 and through said decking, each tie rod passing through a scupper block to locate it relative to said decking, and the upper ends of said tie rods passing upward through said bulwarks and being secured thereto to anchor them firmly to the

35 hull.

4. In a boat hull structure, upright frames, planking secured to said frames and forming an exterior hull wall, a clamp element extending lengthwise of the hull and secured to the sides of

40 said frames opposite said planking, decking including two superposed plywood layers, disposed above said clamp and extending outward above the upper end of said frames and across the upper edge of said planking, bulwarks above said decking,

45 and composed of a plurality of laminations secured together by joints extending generally vertically, circular scupper spacing blocks interposed between the upper surface of said decking and the lower side of said bulwarks to support the latter from said decking, and hooked tie rods having lower hooked ends in hooked engagement with said clamp, extending upward between said

50 frames and through said decking, each tie rod passing through a scupper block to locate it relative to said decking, and the upper ends of said tie rods passing upward through said bulwarks and being secured thereto to anchor them firmly to the

55 hull.

5. In a boat hull structure, decking, hull framework beneath said decking, main bulwarks above and supported by said decking and stopping short of the stem of the hull, means passing through said decking and directly interconnecting said main bulwarks and said hull framework

60 beneath said decking, operable to anchor said main bulwarks firmly to the hull, fore bulwarks above said main bulwarks and having their aft end extending rearwardly into a position overlying and supported by the forward end of said

65 main bulwarks, the forward end of said fore bulwarks being supported by said hull framework independently of said main bulwarks, and means securing the aft end of said fore bulwarks to the forward end of said main bulwarks.

70 6. In a boat hull structure, decking, hull

framework beneath said decking, main bulwarks composed of a plurality of laminations secured together by joints extending generally vertically disposed above and supported by said decking and stopping short of the stem of the hull, means 5 passing through said decking and directly interconnecting said main bulwarks and said hull framework beneath said decking, operable to anchor said main bulwarks firmly to the hull, fore bulwarks composed of a plurality of laminations 10 secured together by joints extending generally vertically, disposed above said main bulwarks and having their aft end extending rearwardly into a position overlying and supported by the forward end of said main bulwarks, the forward end 15 of said fore bulwarks being supported by said hull framework independently of said main bulwarks, and means securing the aft end of said fore bulwarks to the forward end of said main bulwarks.

7. In a boat structure, an exterior hull wall, decking extending outward to such hull wall, hull framework beneath said decking, bulwarks above and supported by said decking, and composed of a plurality of laminations secured together by 20

joints extending generally vertically, and tie bars passing through said decking and having their upper portions passing vertically generally medially between and parallel to the inner and outer faces of and substantially entirely through said laminated bulwarks, and their lower ends secured to said hull framework, said bars thereby directly interconnecting said bulwarks and said hull framework beneath said decking to anchor said bulwarks firmly to the hull.
